US0D1088010S

(12) **United States Design Patent** (10) **Patent No.:** **US D1,088,010 S**
(45) **Date of Patent:** **** Aug. 12, 2025**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Taylor Gerard Carrigan**, San Francisco, CA (US); **Aled Williams**, Llandello (GB)

(73) Assignee: **Apple Inc.**, Cupertino, CA (US)

(**) Term: **15 Years**

(21) Appl. No.: **29/934,225**

(22) Filed: **Mar. 25, 2024**

Related U.S. Application Data

(63) Continuation of application No. 29/840,011, filed on May 25, 2022, now Pat. No. Des. 1,019,686, which is a continuation of application No. 29/787,441, filed on Jun. 7, 2021, now Pat. No. Des. 954,083, which is a continuation of application No. 29/705,048, filed on Sep. 9, 2019, now Pat. No. Des. 921,669.

(57)

CLAIM

The ornamental design for a display screen or portion thereof with graphical user interface as shown and described.

DESCRIPTION

The FIGURE is a front view of a display screen or portion thereof with graphical user interface showing the claimed design.

The broken lines in the Figure show a display screen or portion thereof, and form no part of the claimed design.

1 Claim, 1 Drawing Sheet
